aware

Application July 29, 1937, Serial No. 156,296

11 Claims. (Cl. 179—171)

This invention relates to an arrangement for stabilizing an amplifier system which operates over a range of frequencies but tends to become unstable when subjected to direct current or very low-frequency alternating-current pulses or surges.

One embodiment of the invention is particularly adapted to systems operating over a very wide range of frequencies, the lower frequency limit of which is a very low frequency, such as a video-frequency amplifier used in television systems, while another embodiment of the invention is particularly adaptable for eliminating the beat note or "flutter" developed and reproduced by a modulated-carrier signal receiver tuned to a desired signal when there is present on the same signal channel an undesired signal of nearly, but not exactly, the same carrier frequency. As used in this specification, a low-frequency amplifier refers to an amplifier for amplifying a range of low frequencies, but such amplifier may also amplify a very broad range of frequencies including high frequencies.

In amplifiers required to operate in a very low-frequency band, it is sometimes impractical to use capacitive coupling between successive stages of amplification because very large coupling condensers are required. Furthermore, if it is desired to amplify a very wide range of frequencies, such large condensers, having an appreciable capacitance to ground, place a limit upon the highest frequency which may be amplified without excessive attenuation. Therefore, it has been previously proposed to use a resistance-coupled amplifier without the usual grid condensers, that is, a "direct current" amplifier, to meet the above requirements. However, such an amplifier tends to be unstable at very low frequencies, due to the fact that small fluctuations in the operating conditions of the system have an appreciable effect on its characteristics and cause the amplifier to "drift". Such effect may be caused by a fluctuation in the direct current supply to the system, a change in ambient temperature, faulty contacts in the system, fluctuations in cathode temperature, etc. It has previously been necessary to reduce to a minimum these factors tending to produce an unstable condition in order to procure satisfactory operation of an amplifier of the type mentioned.

Furthermore, in the reception of a desired modulated-carrier signal on a given channel, it frequently happens that signals of a lower order of magnitude are present on the same channel, due to a weak or distant station operating on

the channel. These signals may be modulated by the same program so that the modulation frequencies do not cause objectionable interference, but if the carrier of the undesired signal is not synchronized with that of the desired signal, which is usually the case, a beat note or "flutter" of very low frequency will be present in the audio-frequency channel of the receiver due to the heterodyne action between the desired and undesired signal carriers. The frequency difference between such stations operating on the same channel and thus the beat-note frequency is usually between zero and fifty cycles.

It has previously been proposed to utilize high-pass filters in the audio-frequency channel of the signal receiver to eliminate the undesirable "flutter" described above. A filter circuit producing an attenuation of 20 decibels at 30 cycles without appreciable attenuation above 100 cycles has usually been found sufficient to eliminate most of the "flutter". In general, however, the use of such filters is impracticable for the reason that high-inductance choke coils or high-capacitance condensers, or both, are required in the filter for such low frequencies, resulting in an expensive and bulky construction.

It is an object of the invention, therefore, to provide an amplifier capable of operating over a very wide range of frequencies, the lower frequency limit of which is a very low frequency and which is stable when the system is subjected to pulses or surges of lower frequency or direct current.

It is a further object of the invention to provide a modulated-carrier signal receiver including a simple arrangement for the elimination of the beat note or "flutter" produced therein between a desired signal and an undesired signal which is present on the same channel but which is not synchronized with the desired signal.

In accordance with the invention an amplifier includes means for feeding back a voltage from one point in the amplifying system to a preceding point of the system, the feedback being degenerative primarily at frequencies below the lower limit of the desired range, that is, frequencies of the disturbances causing the amplifier to be unstable or producing an undesirable beat note or "flutter". The feedback becomes decreasingly degenerative with increasing frequency because it is designed to be less effective at frequencies slightly removed from the very low frequencies of the band to be passed or slightly above those frequencies in the system which cause instability or produce an objectionable beat note.

between stations on the same signal channel, so that the normal frequency-response characteristic is not substantially altered over the major portion of the operating frequency range.

5 For a better understanding of the invention, together with other and further objects thereof, reference is had to the following description taken in connection with the accompanying drawing, and its scope will be pointed out in the 10 appended claims.

Fig. 1 of the drawing is a circuit diagram illustrating an embodiment of the invention as applied to a resistance-coupled direct current amplifier; Fig. 2 is a diagram illustrating certain 15 characteristics of the system of Fig. 1; Fig. 3 is a circuit diagram, partly schematic, illustrating an embodiment of the invention as incorporated in a modulated-carrier signal receiver of the superheterodyne type; and Fig. 4 is a diagram illustrating certain characteristics of the 20 receiver of Fig. 3.

Referring now to Fig. 1 of the drawing, there is shown a circuit diagram of a resistance-coupled direct current amplifier having three 25 stages of amplification comprising vacuum tubes 10, 11, and 12. The anode of tube 10 is connected through load resistance 14 and decoupling resistance 15 to a source of supply voltage, such as a battery 16; a decoupling condenser 17 is connected between the common terminal of resistors 14 and 15 and ground. The anode of tube 10 is connected to the control grid of tube 11 through a circuit comprising a resistor 18 and a condenser 19 in parallel, while the control grid of tube 11 is connected to its cathode through a grid-leak 30 resistor 20 and a bias source 21.

The output circuit of tube 11 is connected to the input electrodes of tube 12 in a manner similar to that described for coupling tube 10 to tube 11. Thus the anode of tube 11 is connected through load resistance 22 and decoupling resistance 23 to the source 16; decoupling condenser 24 is connected between the common terminal of resistors 22 and 23 and ground; the anode of tube 11 is connected to the control grid of tube 12 through a circuit comprising a resistor 25 and a condenser 26 in parallel, while the control grid of tube 12 is connected to its cathode through grid-leak resistor 27 and a bias source 28. A coupling 35 system such as has been described above is described in British Patent No. 456,450 to White.

Briefly, the amplifier described above comprises a plurality of amplifying tubes in which the external load impedance of each tube, together with 40 the anode-cathode impedance of the tube, can be represented over a range of frequencies down to and including zero frequency by a pure resistance R_1 (resistors 14, 22) in series with an impedance Z_1 (resistor 15 and condenser 17, resistor 23 and condenser 24). The anode of each tube is connected to the control grid of the succeeding tube through a coupling impedance Z_2 (resistor 18 and condenser 19, resistor 25 and condenser 26). In order to secure a uniform amplification over 45 the range of frequencies to be amplified, the circuit in such amplifier is preferably arranged such that:

$$\frac{Z_2}{Z_1} = \frac{R_2}{R_1}$$

70 when R_2 represents grid resistors 20 or 27.

Coming now to the parts of the system involving the present invention, the system is stabilized by feeding back a voltage from one point in the system to a preceding point in the system. More 75 particularly, the feed-back path is from the com-

mon terminal of resistors 22 and 23 to the common point of resistors 14 and 15 and includes resistors 29, 30, and 31; shunt condensers 29' and 30' connected between the common terminals of resistors 29, 30, and 31, respectively, and ground, forming a conventional ladder filter.

It will be understood that resistor 30 and condenser 30' can be omitted, thus providing a feed-back circuit having only one ladder section, or that more than two ladder sections can be used in the feed-back circuit. The resistance and impedance relationships, as set forth above, with respect to an amplifier having no feedback, are modified by the inclusion of the feed-back circuit in a manner which will be understood by those skilled in the art. The relations needed for the compensating condensers C_{17} and C_{19} which correct for the effect of the feed-back circuit are:

$$\frac{C_{17}R_{15}R_{31}}{R_{15}+R_{31}} = C_{19}R_{18} \quad 20$$

and

$$\frac{R_{15}R_{31}}{(R_{15}+R_{31})R_{18}} = \frac{R_{14}}{R_{20}} \quad 25$$

where $R_{31} = R_{29}$ and the subscripts identify the circuit elements of Fig. 1. The first equation is the condition for equality of the time constants of the correcting or compensating condenser circuits. These time constants should have a value of the same order of magnitude as the period of a frequency considerably greater than the lowest frequency to be amplified and considerably less than the highest frequency to be amplified. This avoids interference between the condenser correcting circuits and the feed-back circuit which operates at a very low frequency. It also avoids interference between the condenser correcting circuits and the inherent capacity of the tube which becomes important at 30 very high frequencies. 35

In considering the operation of the feed-back circuit, it will be seen that the output voltage of tube 10 is subjected to a reversal of polarity as it is transmitted through the tube 11 so that the output voltage of tube 11 is substantially in phase opposition to the input voltage of tube 11. The feed-back circuit applies to the input of tube 11 a voltage derived from the output of tube 11 and having a phase displacement with respect to input voltages of corresponding frequencies which varies as a function of frequency. Thus, for very low frequencies, the impedances of shunt condensers 29' and 30' are very large with respect to the impedances of resistors 29 and 30 and the phase of the feed-back voltage is retarded only slightly by the filter sections of the feed-back circuit; that is, the feed-back voltage is applied to the input circuit of tube 11 substantially in phase opposition with the signal input voltage to this tube so that, at these low frequencies, the system is degenerative. The constants of the feed-back path are such that, at slightly higher frequencies, the impedances of condensers 29' and 30' are substantially less than, and so related to, the 40 impedances of resistors 29 and 30 that the filter network retards the phase of the signal voltage by an amount approaching 180 degrees as a limit and the system becomes progressively less degenerative and actually regenerative; in addition, 45 this feed-back circuit has a time constant proportioned to attenuate or filter out desired signal components of the frequency range. It will also be seen that there is a direct current feed-back path through series-connected resistors 29, 30, 50 55 60 65 70 75 80 85 90 95 100 105 110 115 120 125 130 135 140 145 150 155 160 165 170 and 31, these resistors being proportioned materially to reduce the gain of the amplifier at zero frequency.

In Fig. 2 there are shown three curves representing the frequency-response characteristics of the system of Fig. 1. Curve *a* indicates a uniform response over the operating frequency range and represents the normal operation of the amplifier without the feed-back circuit; curve *b* represents the operation of the amplifier with the feed-back circuit of Fig. 1; while curve *c* is included as an example of the effect which may be obtained by using a single ladder section comprising a series resistor and a shunt capacitor in the feed-back circuit, as, for example, omitting the elements 30, 30' of Fig. 1. An increase in the number of ladder sections in the feed-back circuit may cause the frequency-response characteristic of the system to be slightly irregular above the cutoff frequency and tends to produce a sharper cut off characteristic.

Referring now to Fig. 3, there is shown a circuit diagram of a complete modulated-carrier signal receiver of the superheterodyne type embodying the invention, in which certain conventional portions are schematically shown, since, per se, they form no part of the invention. The receiver comprises in cascade an antenna-ground circuit 32, a radio-frequency selector and amplifier 33, a frequency changer or oscillator-modulator 34, an intermediate-frequency amplifier 35, a detector and automatic amplification control rectifier 36, an audio-frequency amplifier of three stages indicated generally at 37, and a loud-speaker 38. An automatic amplification control bias derived from unit 36 is applied by way of connection 36' to the grids of one or more of the tubes of the several stages of the receiver to maintain the input to the detector 36 within a relatively narrow range for a wide range of received signal intensities.

Audio-frequency amplifier 37 comprises an amplifier tube 39, having its input coupled to unit 36 through a voltage divider volume control 40 and its output circuit coupled through load resistor 41 and coupling condensers 42 and 43 in parallel to an amplifier tube 44, the output circuit of which is coupled through transformer 45, 46 to a stage of push-pull amplification comprising tubes 47 and 48. The common output circuit of tubes 47 and 48 is coupled through transformer 49, 50 to loud-speaker 38. Operating potentials for the tubes of audio-frequency amplifier 37 are supplied from suitable sources as indicated in the drawing.

Neglecting for the moment the operation of the parts of the system involved in the present invention, the system described above includes the features of a conventional superheterodyne receiver. The operation of such a receiver being well understood in the art, a detailed explanation thereof is deemed to be unnecessary. Briefly, however, a desired modulated-carrier signal intercepted by antenna 32 is amplified in radio-frequency amplifier 33 and converted in oscillator-modulator 34 to an intermediate-frequency modulated-carrier signal. This signal is amplified by intermediate-frequency amplifier 35 and translated therefrom to detector 36, where the audio frequencies of modulation and automatic amplification control potentials are derived. The audio frequencies of modulation are successively amplified by amplifier stages 39 and 44 and the push-pull stage of amplification comprising tubes 47 and 48 and are reproduced by loud-speaker 38 in a conventional manner. The automatic amplification control

applied to one or more of the tubes in the preceding stages of the receiver from unit 36 serves to maintain the signal output of the receiver within a relatively narrow range for a wide range of received signal amplitudes, in a conventional manner.

Coming now to the parts of the system of Fig. 3 embodying the present invention, the undesirable beat note or "flutter" described above is substantially eliminated by feeding back a voltage from one point in the audio-frequency channel 37 to a preceding point of the channel. More particularly, the feed-back path is from the secondary winding of transformer 45, 46 to the input circuit of amplifier 39 and includes series-connected switches 51 and 52, resistors 53, 54, 55, and 56 and condenser 57 with shunt condensers 58, 59, and 60 connected between the successive junctions of resistors 53, 54, 55, and 56 and ground to form the conventional ladder-type filter. In order that condenser 42 may be effectively removed from the coupling circuit between tubes 39 and 44 when the feed-back circuit of the invention is in operation, there is provided a switch 61 ganged for unicontrol with switches 51 and 52, 25 as indicated at U in the drawing. A resistor 62, sufficiently large to prevent condenser 42 from having an appreciable coupling effect when switch 61 is open, is connected across the terminals of switch 61 and serves to maintain the charge on the condenser, thereby preventing a click in the loud-speaker when switch 61 is closed. The following circuit constants are given as illustrative of the invention:

	Megohms
Resistor 41	0.1
Resistor 53	0.5
Resistor 54	1.0
Resistor 55	0.5
Resistor 56	2.0 40
Resistor 62	5.0
	Microfarads
Condenser 42	.05
Condenser 43	.007
Condenser 57	.05 45
Condenser 58	.005
Condenser 59	.01
Condenser 60	.01

In considering the operation of the feed-back circuit, Fig. 3, it will be seen that the phase of the signal is subjected to two reversals as it is transmitted through tubes 39 and 44 and to an additional reversal in transformer 46 so that the phase of the output voltage of transformer 45, 46 55 is substantially in phase opposition to the input voltage of tube 39. The feed-back circuit applies to the input of tube 39 a voltage derived from the output of transformer 45, 46 and having a phase displacement with respect to input voltages of 60 corresponding frequencies which varies as a function of frequency. Thus, for very low audio frequencies the impedances of shunt condensers 58, 59, and 60 are very large with respect to those of series resistors 53, 54, and 55 and the phase of the voltage fed back is retarded only slightly by each of the three ladder sections of the network 51-60 and is applied to the input circuit of tube 39 substantially in phase opposition with the signal input voltage, so that at these low frequencies the system is degenerative. The circuit constants of the feed-back path are such that in the vicinity of 100 cycles the impedances of condensers 58, 59, and 60 are substantially less than, and so related to, the impedances of the resistors 75

53, 54, and 55 that each of the three ladder sections of the network retards the phase of the signal voltage approximately 60 degrees so that the final feed-back voltage is in phase with the input voltage and the system becomes regenerative.

5 In order that the regenerative effect of the feed-back circuit shall have no appreciable effect in increasing the over-all gain of audio-frequency amplifier 37 at frequencies above 100 cycles, condensers 57—60, inclusive, are so proportioned that their reactances are sufficiently low at such frequencies that practically no voltage is coupled through the feed-back path to the input circuit of amplifier 39. Furthermore, the shunt effect of 10 these condensers on the input circuit of the push-pull amplifier comprising tubes 47 and 48 reduces the output of the receiver by a slight amount at the higher frequencies which tends to compensate for the regenerative effect of the feed-back circuit and is not objectionable. At the same time, the regenerative action of the feed-back path in the vicinity of 100 cycles tends to produce a marked peak in the response characteristic at this frequency. This is avoided by the opening of 20 switch 61 upon closing switches 51 and 52 to place the feed-back path in operation. Opening of switch 61 is effective to remove coupling condenser 42 from the circuit and, therefore, to reduce the capacitive coupling between tubes 39 25 and 44, thus reducing the response of the system at the lower audio frequencies.

3 In Fig. 4 there are shown the frequency-response characteristics of the receiver of Fig. 3; curve *d* without the feed-back circuit described above, curve *e* with the feed-back circuit, and curve *f* with the feed-back circuit and coupling condenser 42 both removed. It is apparent from Fig. 4 that a substantial attenuation is introduced into the receiver at 30 cycles by the feed-back 40 circuit of the invention. It is also apparent that at frequencies above 100 cycles, the receiver characteristic is not materially altered. It has been found that a receiver characteristic as illustrated at *e* is effective substantially to eliminate the 45 undesirable beat note or "flutter" described above. It will be understood that the feed-back circuit of this invention can be connected across one or more stages of the amplifier to which it is applied and that more than one feed-back path can be employed if desired.

50 While there have been described what are at present considered the preferred embodiments of this invention, it will be obvious to those skilled in the art that various changes and modifications 55 may be made therein without departing from this invention, and, therefore, it is aimed in the appended claims to cover all such changes and modifications as fall within the true spirit and scope of this invention.

60 What is claimed is:

1. A signal amplifier for amplifying a desired range of signal frequencies including low-frequency signals and comprising input and output circuits, a degenerative very low-frequency feed-back circuit between said output and said input circuits, said feed-back circuit including a plurality of series resistors and shunt condensers and having a time constant proportioned to filter out desired signal components of said frequency 70 range, whereby the desired range of frequencies is amplified without substantial interference from undesired very low-frequency fluctuations in the system.

75 2. A signal-amplifying system for amplifying a desired range of signal frequencies including low-

frequency signals, a feed-back circuit from one point of said system to a preceding point thereof, a resistance-reactance network in said feed-back circuit having a time constant proportioned to shift the phase of the feed-back voltage so that 5 said feedback is degenerative at very low frequencies and is regenerative at higher frequencies, whereby undesired low-frequency fluctuations in said system are substantially eliminated, said feed-back circuit having an attenuation proportioned to reduce said feed-back voltage to a negligible value over said desired signal-frequency range.

3. A signal-amplifying system for amplifying a desired range of signal frequencies comprising 15 a direct current amplifier and a degenerative direct current feed-back connection between one point of said system and a preceding point thereof, said connection including series resistors and at least one condenser connected between a junction of said resistors and the return of said feed-back circuit, said resistors and condensers having a time constant proportioned to filter out desired signal components of said frequency range, whereby the desired signal components are 20 amplified without interference from undesired low-frequency and direct current fluctuations in 25 said system.

4. A signal amplifier for amplifying a wide range of frequencies comprising a vacuum tube 30 having input and output terminals, a conductive input circuit coupled to said input terminals, a conductive output circuit coupled to said output terminals, said input and output circuits introducing a minimum capacitance between said input and between said output terminals, and a feed-back circuit from said output circuit to said input circuit comprising a direct current connection for degenerative feedback of direct current fluctuations and a low-pass filter having a time 35 constant such that its cutoff frequency is below said range and signal components of said range are filtered out, whereby alternating currents of 40 said range are amplified without interference from direct current or very low-frequency fluctuations in 45 the system.

5. In a modulated-carrier signal receiver for receiving a desired signal but subject to the reception of an undesired signal on the same signal channel which is not synchronized with said desired signal, an amplifying system comprising an audio-frequency channel, an amplifier in said audio-frequency channel having input and output circuits, a feed-back circuit from the output circuit to the input circuit of said amplifier, the reactive constants of said feed-back circuit having a time constant so proportioned that said feed-back circuit is degenerative at low audio frequencies and regenerative at higher audio frequencies and has an attenuation proportioned to 60 reduce said feed-back to a negligible value at said higher frequencies, whereby the beat note between said desired and undesired signals is substantially eliminated and the receiver characteristics at said higher frequencies are not substantially altered by said feed-back circuit.

6. In a modulated-carrier signal receiver for receiving a desired signal but subject to the reception of an undesired signal on the same signal channel which is not synchronized with said desired signal, an amplifying system comprising an audio-frequency channel, a feed-back circuit from one point of said audio-frequency channel to a preceding point thereof, and a resistance-reactance network in said feed-back circuit hav- 75

- ing a time constant proportioned to filter out desired signal components and to shift the phase of the feed-back voltage so that said voltage is degenerative primarily at low audio frequencies, thereby substantially to eliminate the beat note between said desired and undesired signals.
7. In a modulated-carrier signal receiver for receiving a desired signal but subject to the reception of an undesired signal on the same signal channel which is not synchronized with said desired signal, an amplifying system comprising an audio-frequency channel, a feed-back circuit from one point of said audio-frequency channel to a preceding point thereof, and a resistance-capacitance network in said feed-back circuit having a time constant proportioned to filter out desired signal components and to shift the phase of the feed-back voltage so that said voltage is degenerative primarily at low audio frequencies, thereby substantially to eliminate the beat notes between said desired and undesired signals.
8. In a modulated-carrier signal receiver for receiving a desired signal but subject to the reception of an undesired signal on the same signal channel which is not synchronized with said desired signal, an amplifying system comprising an audio-frequency channel, a feed-back circuit from one point of said audio-frequency channel to a preceding point thereof, and a resistance-capacitance network of the ladder type comprising series resistors and shunt condensers having a time constant proportioned to filter out desired signal components and to shift the phase of the feed-back voltage so that said voltage is degenerative primarily at low audio frequencies, thereby substantially to eliminate the beat notes between said desired and undesired signals.
9. In a modulated-carrier signal receiver for receiving a desired signal but subject to the reception of an undesired signal on the same signal channel which is not synchronized with said desired signal, an amplifying system comprising an audio-frequency channel, a feed-back circuit from one point of said audio-frequency channel to a preceding point thereof, means in said feed-back circuit having a time constant proportioned to filter out desired signal components and to shift the phase of the feed-back voltage so that
- said voltage is degenerative at low audio frequencies and is regenerative at higher audio frequencies, whereby the beat note between said desired and undesired signals is substantially eliminated, and means effective primarily at said higher frequencies for reducing the forward gain in said audio-frequency channel, thereby partially to compensate for the regenerative effect of said feed-back circuit.
10. In a modulated-carrier signal receiver for receiving a desired signal but subject to the reception of an undesired signal on the same signal channel, an amplifying system comprising an audio-frequency channel, a forward coupling capacitance means in said audio-frequency channel, means for selectively connecting a feed-back circuit from one point of said audio-frequency channel to a preceding point thereof, means in said feed-back circuit for shifting the phase of the feed-back voltage so that said voltage is degenerative at low audio frequencies and is regenerative at higher audio frequencies, whereby the beat note between said signals is substantially eliminated, and means for reducing the value of said coupling capacitance means when said feed-back circuit is included in said audio-frequency channel, thereby partially to compensate for said regenerative feed-back.
11. In a modulated-carrier signal receiver for receiving a desired signal but subject to the reception of an undesired signal on the same signal channel, an amplifying system comprising an audio-frequency channel, a forward coupling capacitance means in said audio-frequency channel, switching means for connecting a feed-back circuit from one point of said audio-frequency channel to a preceding point thereof, means in said feed-back circuit for shifting the phase of the feed-back voltage so that said voltage is degenerative at low audio frequencies and is regenerative at higher audio frequencies, whereby the beat note between said desired and undesired signals is substantially eliminated, switching means for reducing the coupling effect of said capacitance means, thereby partially to compensate for said regenerative feedback, and unicontrol means for operating said switching means.

HAROLD A. WHEELER.
